UNITED STATES PATENT OFFICE.

JOSEPH ODIN JOHNSON, OF MENOMONIE, WISCONSIN.

PUMPING ATTACHMENT FOR MOTOR-VEHICLES.

1,298,957.

Specification of Letters Patent.

Patented Apr. 1, 1919.

Application filed November 14, 1917. Serial No. 202,000.

To all whom it may concern:

Be it known that I, JOSEPH ODIN JOHNSON, a citizen of the United States, residing at Menomonie, in the county of Dunn and State 5 of Wisconsin, have invented certain new and useful Improvements in Pumping Attachments for Motor-Vehicles, of which the following is a specification.

The present invention has for its object 10 the provision of a mechanism of such construction as to constitute a simple attachment for motor driven vehicles by means of which the motive power of said vehicle is employed as the driving instrumentality. 15 It will be apparent that such a device must possess as the essential characteristics ready adaptability to different vehicles, a minimum number of parts, ease of attachment and efficiency of action, all of which are 20 typified in my invention which is specifically described in the following specification and illustrated in the accompanying drawing wherein:

Figure 1 is a vertical sectional view of the 25 device; and

Fig. 2 is an end elevation.

Referring to the drawing, 1 indicates the body casting of the pump provided at one side with the cylinder 2 in which the piston 30 3 is mounted and at the other side with a pressure chamber 4. At the lower end of the casting is the suction inlet 5 into which is screwed the nipple 6, the inner end of said nipple constituting a seat for the ball valve 7. Just above the said valve is inserted into 35 the cylinder casting a stop pin 8 limiting the movement of the valve from its seat. The inlet communicates by the passage 9 with the pressure chamber 4 through the restricted 40 passage 10 controlled by the valve 11. This valve is similarly restricted in movement by the stop pin 12. At one side the air chamber is provided with the outlet 13 and at the end the casting has a removable plug 45 14 rendering the interior of the pressure chamber accessible for introduction of the ball valve 11.

At one end the casting is provided with a bearing 15 through which extends the crank 50 shaft 16 connected by the wrist pin 17 to the piston rod 18. The said crank shaft is preferably formed with a shoulder 19 and the casting or body of the pump is held in place against this shoulder by the cap 20 which is 55 fixed to the shaft by the set screw 21. This

cap is suitably threaded as indicated at 22 for attachment to the driving axle of a motor vehicle and it will be understood that the cap is designed to be interchangeable so that the proper connection may be made with 60 vehicles of different sizes or constructions. The cap, it will be apparent, has a triple function in that it constitutes the connecting means for connecting the shaft to the pump, for connecting said shaft to the wheel, 65 and lastly, the said cap constitutes a support for the pump. The casting is swingingly mounted upon the crank shaft 16 and depends therefrom under normal conditions, suitable means being applicable to hold the 70 pump body in this position if desired, such means being preferably connected to the apertured lug 23 at the base of the cylinder casting.

A pump of this character may be utilized 75 as a water pump for washing the vehicle, in which event a suction tube is applied to the nipple 6 and a suitable hose connected with the discharge outlet 13. The pump mechanism, however, may be utilized for pumping 80 air and when it is to be used for these purposes a rear wheel of the vehicle is jacked up and after first removing the usual hub cap the connecting cap 20 is screwed in place. The set screw 21 is then adjusted so as to fix 85 the shaft for rotation with the cap when the motor vehicle is operated.

A very simple, compact and useful article is provided by the mechanism hereinbefore disclosed and one which may easily form an 90 inexpensive part of the equipment of the said vehicle.

Having thus described my invention, what I claim as new is:

A pumping attachment for motor driven 95 vehicles adapted for connection with the driving axle thereof, comprising a body having a cylinder at one side, a piston mounted therein and a pressure chamber at the other side, said body having inlet and discharge 100 ports, a crank shaft on which the body is swingingly supported and connected to the piston, a connecting member threaded at one side for connection with the vehicle axle and engageable with the crank shaft at its 105 other side, and means for fixing the crank shaft to the connecting member for actuation thereby.

In testimony whereof I affix my signature.

JOSEPH ODIN JOHNSON.
